JAMES B. LEFFERSON, OF NEW YORK, N. Y.

Letters Patent No. 74,702, dated February 18, 1868.

IMPROVEMENT IN BUNGS.

The Schedule referred to in these Letters Patent and making part of the same.

TO ALL WHOM IT MAY CONCERN:

Be it known that I, JAMES B. LEFFERSON, of New York, in the county of New York, and in the State of New York, have invented certain new and useful Improvements in Bungs; and do hereby declare that the following is a full, clear, and exact description thereof, reference being had to the accompanying drawings, and to the letters of reference marked thereon.

In the annexed drawings, making part of this specification, A represents a metallic bung, with a flange or rim, a , around its outer edge. B represents a short shaft, which has a flange formed upon it at its centre, and in this flange are formed the cog-teeth $e e$. The outer end of this shaft passes through the centre of the bung, and is made fast to it by means of a nut, C; while the inner end passes through a disk, G, and then has a pin, d , passed through it, to keep the disk from slipping off. The inner face of the disk has two slots or grooves cut in it, and in these grooves lie two sliding knives, D D. These knives have recesses formed in one edge, into which the teeth $e e$ catch. When the disk G is held stationary, and the bung A is partially revolved, the teeth $e e$, acting upon the knives D D, cause them to be thrust out beyond the periphery of the bung, so that they will catch, and cutting their way into the wood of the stave, hold the bung firmly and securely in place.

When the bung is inserted in the hole in the barrel made to receive it, the wood of the stave, fitting against the periphery of the disk G, holds it, while a wrench may be applied to the bung for the purpose of causing it to revolve, and thus thrust out the knives D D. The outer ends of the knives are so bevelled and sharpened that they will readily take into the wood of the stave.

I do not claim a bung, having two parts, with sliding knives between.

What I claim is—

The shaft B, provided with cog-teeth $e e$, in combination with the knives D D, provided with recesses, as described, said knives being arranged to operate between the bung A and case a' , as and for the purposes specified.

In testimony that I claim the foregoing, I have hereunto set my hand, this   day of   , 1867.

JAMES B. LEFFERSON.
